UNITED STATES PATENT OFFICE

103,080

DESIGN FOR A COMBINED BOTTLE AND STOPPER THEREFOR

Frank McIntosh, New York, N. Y., assignor to
Lenthalic Incorporated, New York, N. Y., a
corporation of New York

Application November 27, 1935, Serial No. 59,790

Term of patent 14 years

To all whom it may concern:

Be it known that I, Frank McIntosh, a citizen of the United States, residing at New York city, in the county of New York and State of New York, have invented a new, original, and ornamental Design for a Combined Bottle and Stopper Therefor, of which the following is a specification, reference being had to the accompanying drawing, forming part thereof.

In the drawing:

Figure 1 is a top view of a combined bottle and stopper therefor embodying my design;

Figure 2 is a front view; and

Figure 3 is a side view thereof.

The characteristic features of the design reside in the combination of the angular bottle body provided with a tapering shoulder which merges into a round relatively long neck portion, and a stopper having a tall cylindrical head, said head being spaced above the mouth portion of the neck.

I claim:

The ornamental design for a combined bottle and stopper therefor, substantially as shown and described.

FRANK MCINTOSH.
